UNITED STATES PATENT OFFICE.

GEORGE E. WITHERELL, OF HARTFORD, CONNECTICUT, ASSIGNOR TO THE HARTFORD MACHINE SCREW COMPANY, OF SAME PLACE.

CLUTCHING MECHANISM.

SPECIFICATION forming part of Letters Patent No. 504,770, dated September 12, 1893.

Application filed January 19, 1893. Serial No. 458,917. (No model.)

To all whom it may concern:

Be it known that I, GEORGE E. WITHERELL, of Hartford, in the county of Hartford and State of Connecticut, have invented certain new and useful Improvements in Clutching Mechanism, of which the following is a full, clear, and exact description, whereby any one skilled in the art can make and use the same.

The object of my invention is to provide means for driving a shaft in any desired direction and at varying speeds and to this end my invention consists in the details of the several parts making up the clutch device as a whole and in the combination of such parts as more particularly hereinafter described and pointed out in the claims.

Referring to the drawings: Figure 1 is a detail view in side elevation of part of a screw cutting machine that embodies my invention. Fig. 2 is a longitudinal section taken on a vertical plane passing through the axis of spindle *a* in Fig. 1. Fig. 3 is a detail view in cross section through the device on plane denoted by line *x*—*x* of Fig. 1 and looking toward the right. Fig. 4 is a detail view in cross section through the clutch parts looking toward the left. Fig. 5 is a detail view on enlarged scale showing the adjacent ends of a split ring with part cut away to show construction. Fig. 6 is a detail end view of the eccentric pivot of the cam. Fig. 7 is a detail side view of the same. Fig. 8 is a detail plan view of the locking ring. Fig. 9 is a detail edge view of the same. Fig. 10 is a transverse section taken on the line *y*—*y* of Fig. 1, showing a face view of the fixed ring and the clutching mechanism co-operating therewith.

In the within drawings and specification my invention is shown and described as embodied in part of a screw machine in which the object is to drive the work holding spindle forward with a fast motion, then to continue the forward motion of the spindle with a slow motion, and after that to drive it in a reverse direction with a fast motion in order to accomplish a special work to be done on the machine. My improvement is equally applicable, however, without material change to any shaft to which it is desired to give a rotary movement at different speeds in one

direction or in opposite directions at the same or at different speeds.

In the accompanying drawings the letter *a* denotes the spindle that is supported in bearings *b* in the frame *b*. A loose pulley *c* is mounted on the shaft and preferably arranged next to the bearing, the hub *c'* affording a proper lateral bearing for the pulley. On one side of the pulley *c* there is formed a socket *c*² in which a split ring *d* forming part of the clutch mechanism is located. This ring is secured at one or more points to the disk *e* that fits closely within an expanding ring located in the socket *c*². The hub of this disk is secured to the shaft as by means of a clamping screw *e'* extending through the hub on the disk and engaging the shaft so that the disk and shaft will move together. On the shaft there is also supported a sliding collar *g* which has a limited reciprocating movement and is provided with projecting arms *g'* that extend through openings *e*³ in the disk, one set of the arms having sockets *e*³ into which the end of a toggle-arm *h* projects. This collar has an annular groove *g*² formed in its periphery and adapted to receive the forked end of a shifter lever by means of which this clutch part may be moved lengthwise of the shaft. The split ring *d* fits snugly within the socket *c*² in the side of the pulley and is so arranged that when expanded it will grasp the pulley with a firm hold.

The expanding device comprises a cam block *i* pivoted to the end of the ring at one side of the opening *d*' and having an end bearing a cam *i'*, the surface of which engages the cam surface *d*² formed on the opposite end of the split ring. This cam block is mounted on an eccentric *j*' formed midway of the pin *j*, one end of which fits a socket in the ring on one side of the block, while the other extends through a locking ring *j*² that is seated in a threaded socket in the side of the split ring *d* and on the opposite side of the block. This pin is tapered so as to fit a tapered perforation in the nut. The object of this construction is to enable the center of the pivot which supports the cam block to be set at any distance within the throw of the eccentric from that end of the ring which bears

the cam surface. This adjustability of the cam block enables the degree of expansion of the ring by the sliding movement of the collar to be nicely adjusted. The cam block is 5 operated by a toggle *h* that is pivoted to the back of the block and has its opposite end in engagement with the socket in the arm *g'* of the sliding collar *g*. A similar arrangement of clutch parts is connected to the pulley *f*, 10 the sockets in these respective pulleys *c, f*, being formed in adjacent sides of the pulley, the sliding collar operating to engage the pulley *c* at one end of its sliding movement and the pulley *f* at the other end of its play. The 15 hub of the disk appurtenant to the clutch mechanism of the loose pulley *f* is clamped to the shaft by the set screw *e'* so as to turn with it. The pulley *c* is normally driven at a rate of speed in the direction of the arrow shown in 20 Fig. 1 that will cause it when connected to the shaft to drive the latter forward with a fast motion. The pulley *f* is driven normally in a reverse direction and at a speed that will cause it when clutched to the spindle *a* to give 25 the latter a fast motion except when the movement of this latter pulley is translated and reduced by means of a system of gears. A sleeve *l* is arranged on the spindle, its hub being secured to the hub of the pulley *f* as by 30 means of a key *l'* so that the sleeve will be driven with the pulley *f*. On the outer end of this sleeve is a pinion *l''* the teeth projecting from the surface of the sleeve a slight distance sufficient to form a shoulder between 35 which and the face of the pulley *f* the hub *m'* of a disk *m* is held, but free to revolve on the sleeve. A fixed ring *n* is secured to the bed *b* and within this ring is arranged a split ring *n'* similar in construction to the one al- 40 ready described as forming part of the clutch mechanism appurtenant to the pulleys *d* and *f*. The disk *m* may be clamped to the ring *n* through the medium of the expanding ring *n'* by a sliding movement of a collar *o* that is 45 loosely mounted on the hub *m'* of the disk *m* and is engaged with the ring *n'* by means of a toggle lever *h'*. An annular gear *p* having teeth upon the inside, as shown in Fig. 4 of the drawings, is arranged so as to overhang 50 the pinion *l''* and leave an annular space between the two gears. This annular gear is secured to or forms part of a disk *p'*, the hub of which is keyed to the spindle *a* by a key *t* so as to turn with it. Intermediate gears *q* 55 are mounted on the disk *m* on pins or pivots *q'* with their teeth engaging the annular gear *p'* and the teeth of the pinion *l''*. When the disk *m* is clamped to the fixed ring by means of the shifting device *o* operated by any convenient form of shifting lever it will be anchored to the fixed ring *n* through the instrumentality of the toggle *h'*, cam block *i* and the split ring *n'* and thus hold the intermediate gear *q* in a fixed position with respect 60 to the axis of the spindle *a*. The result of this will be that the pinion *l''* which is driven

in the same direction as the pulley *f* will turn the intermediate gears in a reverse direction owing to the fact that the disk on which these gears are pivoted is held fast against any turning movement. The intermediate gears *q* gearing into the annular gear *p* drive the latter in a reverse direction or in the same direction as that in which the pinion turns and as this annular gear *p* is secured to the spindle it will drive the latter in the same direction but with a slower speed. As the pulley *f* turns in a reverse direction to the pulley *c* it will be seen that this slow motion of the spindle *a* is in a reverse motion and at a slower 80 speed than is the motion given to the spindle *a* by means of the pulley *c*. By unclutching the disk *m* by a reverse motion of the shifter collar *o* the spindle *a* is released and it may be then driven forward with a fast motion by 85 the operation of the clutching mechanism appurtenant to the pulley *f*, that is, by moving the sleeve *l* so as to cause the clutching mechanism to clamp the pulley *f* to the disk appurtenant of the clutch mechanism of that 90 pulley, the hub of said disk being secured to the spindle *a* as by means of the clamping screw *e'* that passes through it into the spindle. The spindle *a* is idle and not affected by this driving mechanism of course when the 95 several clutch devices are disengaged.

In the accompanying drawings the device is shown with parts arranged so as to drive the spindle in a reverse direction with a fast motion.

I claim as my invention—

1. In combination with a spindle and its bearings, mechanism for driving the spindle with a variable speed and comprising a loose pulley mounted on the shaft and driven in 105 one direction, a second loose pulley mounted on the shaft and driven in a reverse direction, the clutch mechanisms as described appurtenant to the pulleys, a sleeve secured to one of the pulleys and turning with it and 110 having on its outer end a pinion, an annular gear fixed on a disk secured to the spindle, a fixed ring appurtenant to the annular gear the disk of the clutch mechanism appurtenant to the fixed ring supporting an intermediate gear located between the annular gear and the pinion and the clutch mechanism appurtenant to the fixed ring, all substantially as described.

2. In combination with a spindle and its 120 bearings two loose pulleys mounted on the shaft and driven normally in opposite directions, clutch mechanisms located between the adjacent faces of the pulleys and adapted to clamp either of them to the shaft a shifter 125 ring that is arranged in operative connection with the clamping parts of the clutch device, a sleeve bearing a pinion secured to one of the pulleys and turning with it and the described mechanism including a fixed ring and 130 clutch and the annular and intermediate gears whereby the rotary movement of the

pulley bearing the sleeve and pinion is reduced in speed, all substantially as described.

3. In a clutch mechanism the combination of an expanding ring, a cam block pivoted to one end of the ring on one side of the opening and having on the outer end a cam face cooperating with a cam formed on the end of the ring on the opposite side of the opening, and an eccentric pivot hinging the cam block to the ring, all substantially as described.

4. In combination in a clutch mechanism, an expanding-ring, a pivot-pin bearing an eccentric arranged across a socket in one end

of the ring and having one end tapered, and a nut screwed into the side wall of the socket 15 and holding the pin in place and having a tapered perforation into which the tapered end of said pin fits, and a cam-block mounted on the pin and having a cam face cooperating with a cam surface on the opposite end of the 20 ring, all substantially as described.

GEORGE E. WITHERELL.
